UNITED STATES PATENT OFFICE.

JOHN F. O'CONNOR, OF CHICAGO, ILLINOIS, ASSIGNOR TO WILLIAM H. MINER, OF CHAZY, NEW YORK.

FRICITION SHOCK-ABSORBING MECHANISM.

Application filed September 8, 1921. Serial No. 499,208.

To all whom it may concern:

Be it known that I, JOHN F. O'CONNOR, a citizen of the United States, residing at Chicago, in the county of Cook and State of Illinois, have invented a certain new and useful Improvement in Friction Shock-Absorbing Mechanisms, of which the following is a full, clear, concise, and exact description, reference being had to the accompanying drawings, forming a part of this specification.

This invention relates to improvements in friction shock absorbing mechanisms.

One of the objects of the invention is to provide a simple and efficient draft rigging.

Another object is to provide a draft rigging in which the friction elements and the associated spring elements travel with different rates of speed, with the beneficial results hereinafter described.

Other objects will appear from the explanation of an embodiment of my invention, hereinafter following.

In the drawings forming a part of this specification, Figure 1 is a horizontal view, partly in plan of a draft rigging for railroad cars embodying my invention. Figure 2 is a cross-section taken on line 2-2 of Figure 1. Figure 3 is a horizontal sectional view of the draft gear shell, with its contained parts shown in their positions when under full compression, the view shown in Figure 1 illustrating their normal position. Figure 4 is a cross-section taken on line 4-4 of Figure 1. Figure 5 is a sectional view taken on line 5-5 of Figure 4. Figure 6 is a sectional view taken on line 6-6 of Figure 4. Figure 7 is a perspective view of the spring follower. Figure 8 is a perspective view of one of the friction plates. Figure 9 is a perspective view of one of the inner friction plates. Figure 10 is a perspective view of one of the wedge elements.

Referring to the drawings, the numerals 11-11 indicate draft members, or parts of the car frame to which the draft rigging is applied. The rear stop members are indicated by the numerals 12-12 and the front stops are shown at 13-13. The draw-bar 14 is transversely slotted to receive the coupler key 15, which extends at its ends thru the slots 113 in members 13 and the elongated slots 16 registering therewith and formed in the adjacent parts of the draft members 11. The coupler key 15 also ex-

tends thru the slots 17 in the head 18 of the yoke 19. The yoke surrounds the front follower 20 and the compression-resisting member 21, all of which are held in their position between the draft members 11 by means of the tie plate carrier 22, which is suitably secured to the draft members 11, as for instance, by the bolts 23. The compression resisting member comprises the shell 24 and the contained spring elements 25 and the friction elements 26. The particular spring elements shown in the drawing are made up of the two pairs of inner-nested springs 27-27 which are rearwardly seated against the internal face of the rear closure plate 28 of the shell and are forwardly seated against the spring follower 29. The friction elements are made up of friction plates and a wedging or spreading device therefor, the friction plates comprising the longitudinally movable plates 30-30 and the plates 31 which are stationary longitudinally but are capable, together with the movable plates 30, of a lateral movement as occurs when under spreading pressure of the wedging members.

The said plates 31, which for convenience we call the stationary plates, are provided with upper and lower shoulders 32 and 33, respectively, adapted to engage within the upper and lower transverse slots 34 and 35, respectively, formed in the shell and are thereby held against longitudinal movement while permitted to move laterally in the said slots. Rearwardly the said plates are each provided with a slot 36 for the entrance of the forwardly extended flange 37, with which the spring follower 29 is provided. The movable plates 30 are ordinary flat plates which extend rearwardly and engage against the spring follower.

The inner plates 31-31 are each provided, on the face adjacent the wedging mechanism, with a wedging face 40 which cooperates with elements of the wedging mechanism hereinafter described. The wedging mechanism includes the central wedge member 41, perforated as at 42 for the passage of the bolt 43 which, at its rear end, passes thru the perforation 44 in the spring follower 29 and is provided with a head 45, which is received within the hollow box-like portion 46 of the spring follower 29. The wedge member 41 extends between a pair of supplementary wedge members 47-47, each of

which is substantially triangular in horizontal section, as is most clearly shown in Figure 10 and each is provided on its inner edge with a groove 48 for the passage of the bolt 43. The supplementary wedge members each engage the adjacent wedge face 40 provided upon each of the internal stationary friction plates hereinbefore described. The supplementary wedge members 47, together with the central wedge member 41, are held against accidental displacement by the bolt 43 and by the forwardly extended vertically spaced apart wings or flanges 49-49, with which the spring follower is provided.

From the foregoing description in connection with the drawings it will be clear that upon rearward movement of the draw-bar the front follower 20 will force the central wedge member 40 rearwardly, which action will tend to spread the supplementary wedge members, which will move outwardly upon the front face 50 of the spring follower and that the spring follower, in its retreat against the pressure of the springs behind it, will permit this lateral movement, and meanwhile the supplementary wedge members will press laterally outwardly against the faces 40 upon the adjacent stationary friction plates, forcing them and the series of plates between them and the outer edges of the shell into close friction-developing and movement-resisting contact. It will be apparent that as the spring follower retreats, by reason of the lateral, as well as the rearward movement of the supplemental wedge members, it will not retreat as rapidly as the central wedging member 41 or as rapidly as the follower which engages it moves inwardly.

In normal position of the parts, the front follower 20 is spaced away, as indicated at 51, from the front ends of the longitudinally movable friction plates 30, and when in its rearward travel the said follower engages the front ends of the said friction plates, the spring follower 29 will have moved rearwardly a lesser distance than the front follower 20 and assumed a spaced relation with reference to the inner ends of the movable plates. Upon the engagement of the front follower against the longitudinally movable friction plates the same will slide rearwardly, generating friction against the sides of the intercalated stationary plates. While the movable friction plates are being moved rearwardly by the front follower, the spring follower will also move rearwardly but a lesser distance than the front follower and the movable plates and the distance between the inner ends of the movable friction plates will gradually decrease until the spring follower again touches the rear ends of the movable plates as illustrated in Fig. 3. 65 When the parts reach this position, the

spring elements 25 in back of the spring follower 29 will be compressed more rapidly than theretofore, because the spring follower will move at the same rate as, and in unison with, the front follower, wedging elements and movable friction plates. It will thus be seen that by reason of the action and arrangement of the wedging member the spring elements will move relatively slowly during the initial movement of the follower until the intercalated plates have been tightly compressed and relatively fast toward the end of the follower's movement. Upon release of the pressure of the drawbar the parts under the pressure of the spring elements will return to their normal position, as it is shown in Figure 1 of the drawings. On forward movement of the drawbar the front follower is held against forward movement by the front stop members and by means of the yoke, the drawbar pulls the shell forwardly, the wedge resting against the front follower and the action of the parts within the shell being similar to that occurring upon rearward movement of the drawbar, as will be understood.

I have herein shown and described what I now consider the preferred manner of carrying out the invention, but the same is merely illustrative and I contemplate all changes and modifications that come within the scope of the claims appended hereto.

I claim:

1. In a friction shock absorbing mechanism, in combination, a shell; spring elements; friction plates; wedging elements; and a spring follower, said spring elements, friction plates, wedge elements and spring follower being located within the shell, the spring follower being provided with spaced apart forwardly extended wings to receive the wedge elements, the wedge elements comprising a central wedge member and lateral supplemental wedge members, the friction plates comprising intercalated longitudinally movable and longitudinally immovable plates, one of the latter plates being adjacent each of the supplementary wedge members and having an angular wedging face engaging a supplementary wedge member, the supplementary wedge members moving laterally away from each other upon the spring follower on inward movement of the central wedge member and moving rearwardly with said follower, the said follower being yieldingly held by the spring elements.

2. In a friction shock absorbing mechanism, in combination with a front follower; of a column-load sustaining shell; a spring resistance; a spring follower co-acting with said spring resistance; opposite groups of intercalated friction plates within the said shell, each group comprising longitudinally movable plates and longitudinally fixed

- plates, all responsive to lateral pressure, the front ends of said movable plates being spaced a substantial distance from said front follower and adapted to be actuated thereby, 5 after a predetermined movement of the latter; a central wedge element interposed between said group of plates, said element being provided with a pair of inwardly converging wedge friction faces; a pair of auxiliary wedge elements interposed between said central element and said intercalated plates, said auxiliary wedge elements each having a wedge friction face co-acting with a wedge friction face of said central wedge 10 element a flat face co-acting with said spring follower and a friction wedge face co-acting with the innermost friction plate of the adjacent group of plates, said innermost friction plate being one of said longitudinally fixed plates, the oppositely disposed innermost fixed plates of said groups of plates being provided with inwardly diverging wedge friction faces co-acting with the adjacent wedge friction faces of said auxiliary 15 20 25 30 35 40 45 50 55 60 65 plates, and flat friction faces co-acting with the adjacent movable plates, said auxiliary wedge elements having sliding movement upon the spring follower and longitudinal movement therewith, whereby all the lighter initial shocks are absorbed by said wedge friction elements and a wedging pressure is transmitted to said friction plates.
3. In a friction shock absorbing mechanism, the combination with a shell; of a front follower; a plurality of laterally displaceable friction elements held against longitudinal movement relative to the shell; movable friction plates intercalated with the stationary elements, said movable plates having their front ends spaced from the follower, and adapted to be actuated by the latter after a predetermined movement thereof; a pressure creating friction wedge system co-acting with said intercalated plates and elements, said wedge system comprising a central wedge member and a pair of auxiliary wedge members, all of said wedge members being provided with co-acting wedge friction faces, and each of said auxiliary wedge elements being provided with an additional friction wedge face adapted to co-act with one of said friction elements; a spring resistance within the shell; and a spring follower interposed between said wedge system and said spring resistance.
4. In a friction shock absorbing mechanism; the combination with a shell; of a front follower; oppositely disposed groups of intercalated relatively stationary and movable friction plates within said shell, said movable plates having their forward ends spaced a substantial distance from said front follower; a combined friction and pressure creating means interposed between
- said oppositely disposed groups of plates, said means comprising a centrally disposed friction wedge member, sliding auxiliary friction wedge members arranged on opposite sides of said central wedge member, having wedge friction faces co-acting with the wedge friction faces of said centrally disposed wedge member, and a wedge friction block interposed between each auxiliary wedge member and the adjacent group of friction plates, each wedge block having a friction face co-acting with the adjacent friction plate and a wedge friction face co-acting with a wedge friction face on one of said auxiliary wedge members, said wedge blocks being held against movement longitudinally of the shell but permitted to have lateral movement therein; a spring resistance within the said shell; and a spring follower interposed between said members and said spring resistance, said follower being provided with a flat face upon which said auxiliary wedges are adapted to slide laterally.
5. In a friction shock absorbing mechanism, the combination with a friction shell; of laterally spaced groups of friction plates, each group comprising alternated relatively stationary and longitudinally movable plates, the movable plates having their outer ends extended outwardly beyond the end of the shell; a spring resistance; a spring follower interposed between said resistance and the inner ends of said movable plates and normally engaging the latter when the mechanism is in full release; an outer follower normally spaced a predetermined distance less than the full permissible movement of the outer follower, from said outer ends of the movable plates; and a plurality of wedge friction elements, including elements longitudinally and laterally movable, interposed between said two followers and between the two groups of plates, operative to move the spring follower in the same direction as, but at a slower rate than, the outer follower when the latter is actuated and thereby space said spring follower from the inner ends of the movable plates during the approach of the outer follower to the outer ends of said movable plates, said wedge friction elements being so operative, after the outer follower engages and actuates the movable plates in unison therewith, to permit the spring follower to approach the inner ends of the movable plates during the continuation of the compression stroke of the mechanism.
- In witness that I claim the foregoing I have hereunto subscribed my name this 31st day of Aug., 1921.
